ADJUSTABLE ARCH SUPPORT

Application filed December 8, 1931. Serial No. 579,776.

The present invention relates to arch supports for footwear, and more particularly to an arch support which is adjustable to vary the height and curvature of the plate to provide the required support for the several arches of the foot.

As the normal foot of a human being in standing position has three principal points of contact with the ground, namely, the heel, the base of the great toe, and the base of the little toe, and four arches in between these points of contact, namely, the anterior metatarsal arch extending across the foot under the metatarsal bones, the inner longitudinal arch extending from the joint of the great toe to the heel, the outer longitudinal arch extending from the joint of the little toe to the heel, and the transverse arch which crosses the foot at the instep, the present invention has in view the provision of an arch support with three points of adjustment arranged substantially at the center of the several arches, in order to provide the proper support therefor and to correct defects therein.

Another object of the invention is the provision of an arch-supporting plate which is curved or arched to conform to the natural shape of the instep of a normal foot, and with the rearward end of the plate recessed to accommodate the ball of the heel and with the forward end cut away on each side edge to form a forward extension arranged to underlie the anterior metatarsal arch substantially at the center thereof.

Another object in view is the provision of an arch-supporting plate and an inner sole secured thereto extending coextensive of the shoe at the heel and forwardly of the shoe under the points of support at the base of the great and little toes.

Still another object in view is the provision of means secured to the sole of the shoe for adjusting the arch-supporting plate from without the shoe, said means providing a positive adjustment of the plate and being provided with means for locking the plate when in adjusted position.

Still another object of the invention is the provision of two plate supporting and ad-

justing means which rigidly secures the plate in position in the shoe but which permits the flexing and free movement of the plate at its ends.

Still another object in view is the provision of an arch support of the character described constructed to prevent the entrance of water or moisture into the shoe at the points of adjustment.

Still other objects reside in novel features of construction and arrangement of parts, which will be more fully described and claimed hereinafter.

The invention is illustrated in the accompanying drawings, in which

Fig. 1 is a bottom plan view of a shoe having the improved arch support;

Fig. 2 is a top plan view of the shoe with a portion of the upper cut away to show the arch support in position therein;

Fig. 3 is a longitudinal sectional view on line 3—3 of Fig. 2;

Fig. 4 is a similar view to that shown in Fig. 3, but with the arch support raised;

Fig. 5 is a detail perspective view of the several parts embodying the invention;

Fig. 6 is a detail top plan view of the sole, showing the arch support in position therein and showing, in dotted lines, the three principal points of support of the normal human foot in standing position and the arches between these points of contact.

In the embodiment of the invention illustrated in the accompanying drawings, the invention is applied to a shoe for the right foot. It is to be understood that the invention is applicable to footwear generally, and the parts illustrated applying to the right shoe are the same in construction for a shoe to be worn on the left foot with the exception that the supporting plate is shaped to conform to the shape of the left foot.

In carrying out the invention, an arch-supporting plate 10 is adjustably secured to the sole of the shoe to support the arches of the foot of the wearer in the region of the instep. The support 10 is raised or arched longitudinally and is provided with a raised lip 11, which is adapted to give support to the side of the foot in the region of the instep. The

said plate is shaped to conform to the natural shape of the instep of a normal foot and is recessed at its rearward edge, as shown at 12, to accommodate the heel of the foot, so that the ball of the heel does not bear on the said support. The lateral side edges 13 and 14 are curved to correspond with the curvature of the sole of the shoe, or what is termed the "last" of the shoe, the lip 11, hereinbefore described, likewise being curved in this manner. The forward portion of the said plate is cut away on each side to provide a forward extension 15 which is positioned to underlie the ball of the foot. Constructed in this manner, the said plate provides a support for the several arches of the foot, as shown in Fig. 6.

The normal foot of a human being in standing position has three principal points of contact, namely, the heel indicated by the circle 16 in Fig. 6, the base of the great toe, and the base of the little toe, indicated by the ovals 17 and 18, and between these points of contact the normal foot has four arches, the anterior metatarsal arch, indicated in Fig. 6 by the dot-and-dash line 19, extending across the foot under the metatarsal bones, the inner longitudinal arch, indicated by the dot-and-dash line 20, extending from the joint of the great toe to the heel, the outer longitudinal arch, indicated by the dot-and-dash line 21, extending from the joint of the little toe to the heel, and the transverse arch, indicated by the reference numeral 22, which crosses the foot at the instep. The plate 10 constructed as hereinbefore described, is adapted to give the required support to these arches and to correct defects therein. For the purpose of adjusting the degree of support to be given to the several arches, provision is made for raising or lowering the plate at points under the said arches, the said plate being preferably constructed of spring metal so that substantially any curvature may be obtained in the plate as required.

As shown in the drawings, the plate is made adjustable at a plurality of points, one point of adjustment being under the inner longitudinal arch substantially midway between the ball of the heel and the joint of the great toe; another point of adjustment being under the outer longitudinal arch and substantially midway between the ball of the heel and the joint of the little toe. These two adjustments are in line and under the transverse arch. A third point of adjustment is provided under the ball of the foot and slightly in back of the joints of the several toes.

Adjustment is obtained at each of the first two points by turning a screw 23, the head 24 of which projects through an opening 25 in a plate 26, said plate being disposed in a recess in the bottom of the outer sole so that the outer face of said plate is flush with the

under surface of the sole. The screw 23 is provided with an integral flange 27, which is arranged in position in the said recess in the bottom of the outer sole against the inner face of the plate 26, the said screw being threaded to engage the threaded opening in a cylindrical sleeve 28. The arrangement of the flange 27 in the said recess prevents longitudinal movement of the screw 23 when the same is turned. The sleeve 28 is provided with a collar 29 arched to conform to the curvature of the plate 10 and with a tubular extension 30 projecting above the said collar. The said collar is riveted to the plate 10 and to an inner sole 31 positioned on top of the said plate, by rivets 32 extending through openings 33 in the inner sole 31 and through openings 34 and 35 in the plate 10 and the collar 29, respectively. The tubular extension 30 projects through an opening 36 in the plate 10 and through an opening 37 in the inner sole 31 to lie flush with the upper surface thereof. The said sleeve is slidably mounted in a tubular member 38, one end of which is provided with a disk or flange 39 disposed in a cylindrical recess in the inner sole of the shoe, the opposite end of the tubular member being disposed in a recess in the flange 27 of the screw 23 to hold the screw in position against the inner surface of the plate 26. The sole of the shoe is cut out to accommodate the tubular member 38, said tubular member being secured to the plate 26 by rivets 40 engaging openings 41 in the plate 26 and openings 42 in the collar 39. This construction rigidly secures the plate 26 and the tubular member 38 in the sole of the shoe and the screw 23 in position, whereby turning the screw by engagement of a proper tool with the head thereof will effect a raising or lowering of the sleeve 28 with a corresponding adjustment of the plate 10. When the plate 10 is adjusted to the elevation desired, a locking screw 43 arranged in an opening 44 in the plate 26, is adapted to engage one of the threaded openings 45 in the flange 27 to lock the screw from further turning movement, thus holding the plate in fixed position. It is to be understood that the plate 26 and the flange 39 are tightly drawn together by the rivets 40, thus preventing water or moisture entering the shoe through the opening in the tubular member 38.

Arranged under the forward extension 15 of the plate 10, is an adjustable metallic plate 46, which is oval in shape and is arched, as shown in Figs. 3 and 4. This plate is provided with slots 47 extending inwardly from the outer edge thereof to provide a series of flexible sections, and centrally of the said plate a plurality of openings 48 are provided for engagement with the upwardly extending stud 49 to provide a series of adjustments of the plate 46 on the collar 50 of a cylindrical sleeve 51. This sleeve is slidably mounted in

5 a tubular member 52, which is similar in construction to the tubular member 38 and is arranged in a cylindrical recess in the sole of the shoe, the lower end of the said member bearing against the shoulder 53 of a screw 54 which screw is arranged to engage the interior threaded opening in the sleeve 51. An outer plate 55, similar to the plate 26, is riveted to the flange 59 of the tubular member 52, by rivets 56 extending through openings 57 in the plate 55, through the shoe sole, and through openings 58 in the said flange 59.

10 When the sleeve 51 is adjusted to the elevation desired, a locking screw 60 arranged in an opening 61 in the plate 55, is adapted to enter one of the threaded openings 62 in the shoulder 53, to lock the screw 54 against further movement. The collar 50 of the sleeve 51 has its upper surface beveled to correspond with the curvature of the plate 46, and it is to be understood that the stud 49 may engage any one of the openings 48 in the said plate to provide means for holding the plate 46 in various positions. When the 15 plate 46 is in the desired position on the collar 50, the said plate may be riveted thereto by rivets engaging openings 63 in the collar 50. A leather covering 64 is provided for the plate 46, as shown in detail in Fig. 5, this covering being riveted to the said plate by rivets 65 engaging openings 66 in the covering 64 and openings 48 in the said plate. The covering 64 being arranged between the extension 15 and the plate 46, prevents the forward portion of the plate 10 from wearing contact with the inside sole of the shoe and while supporting the forward extension 15 the said extension is free to flex when the weight of the wearer bears upon said extension. The said plate 46 and its supporting and adjusting means hereinbefore described may constitute an independent arch support for the anterior metatarsal arch.

20 The sole within the shoe at the heel is cut out on the curved line 67 to correspond to the recess 12 in the plate 10, so that the upper surface of the plate 10 and the heel of the shoe form a substantially continuous surface. The inner sole 31 is coextensive of the shoe at the heel and of said plate and extends forwardly of said plate to underlie the ball of the foot and the points of support at the base of the great toe and the base of the little toe.

25 From the foregoing it will be understood that the plate 10, being formed of spring metal, is flexible to a certain extent, and may be adjusted in elevation to give the required support for the several arches of the foot of the wearer. The adjustments are made by turning the screws 23 and 54, which will produce a vertical movement of the sleeves 28 and 51, respectively, with a corresponding movement of the plate 10. The plate 46 is also 30 constituted of spring metal, and being pro-

vided with flexible sections formed by the slots 47, will conform to the shape of the arch at the ball of the foot. Before this plate is adjusted to the desired elevation, a pin 68 is adapted to fit into one of the openings formed by aligning the grooves 69 in the sleeve 51, with the grooves 70 in the bore of the tubular member 52 to prevent rotary movement of the plate 46. This plate is shaped, as shown in Fig. 5, to conform to the shape of the depression of the anterior metatarsal arch of a normal right foot. It is to be understood that for a shoe for the left foot, the said plate is similarly shaped to conform to the anterior metatarsal arch of a normal left foot.

35 The plate 10 as hereinbefore described being secured adjacent each side edge to the sole of the shoe, thus preventing displacement of the plate to one side or the other, and being unsecured at its ends, is free to bend or flex when the weight of the wearer is placed thereupon.

I claim:

1. The combination of a shoe, and an arch support including a plate arranged on the inside of the shoe, means supporting the said plate arranged adjacent each side edge of the sole of the shoe forwardly of the heel, and a third support arranged in the sole of the shoe for supporting said plate under the ball of the foot.

2. The combination of a shoe, and an arch support including a plate arranged on the inside of the shoe, and means supporting the said plate adjacent each lateral edge thereof forwardly of the heel.

3. An arch support for a shoe including an arched plate arranged on the inside of the shoe, and adjustable means fixedly supporting the said plate adjacent each lateral edge thereof and for adjustably regulating the height of the arch of the plate.

4. The combination of a shoe, and an arch support including an arched plate arranged on the inside of the shoe, means secured to the said plate adjacent each side edge thereof for supporting the arch of the plate, and means cooperating with the first-mentioned means extending through the sole of the shoe for adjusting the height of the said plate at each side edge thereof.

5. The combination of a shoe, and an arch support including an arched plate arranged on the inside of the shoe, the said plate having its rearward edge recessed and its side edges at the forward end cut out to form a forward extension to underlie the ball of the foot, and means secured to the sole of the shoe for supporting the arch of the plate and the said forward extension.

6. The combination of a shoe, and an arch support including an arched plate arranged on the inside of the shoe, the said plate having its rearward edge recessed and its side

- edges at the forward end cut out to form a forward extension to underlie the ball of the foot, and adjustable means secured to the sole of the shoe for regulating the height of the 5 arch of the plate and the height of the said forward extension.
7. The combination of a shoe, and an arch support including an arched plate, a tubular member threaded interiorly secured to the 10 said plate adjacent a side edge thereof, a plate secured to the inner sole of the shoe, said plate being provided with a tubular extension in which the said tubular member is slidable, and a screw extending inwardly 15 through the sole of the shoe and engaging the interior threaded opening in the said tubular member, said screw providing means for adjusting the height of the arch of the first-mentioned plate.
8. The combination of a shoe, and an arch support including an arched plate, a tubular member threaded interiorly secured to the 20 said plate, a plate secured to the inner sole of the shoe, said plate being provided with a tubular extension in which the said tubular member is slidably mounted, a plate secured to the outer sole of the shoe, and a screw provided with a flange adjacent one end thereof, said flange being arranged between the said 25 last-mentioned plate and one end of the said tubular extension and in position to engage the interior threaded opening of the said tubular member to regulate the height of the arch of the first-mentioned plate.
9. The combination of a shoe, and an arch support including a plate arched longitudinally arranged on the inside of the shoe, the forward end of said plate being provided with an extension relatively narrower than 30 the body of the plate, said extension being arched to form a continuation of the arch of the said plate, and means under the said forward extension for regulating the height of the said extension.
10. The combination of a shoe, and an arch support including a plate arched longitudinally arranged on the inside of the shoe, the forward end of said plate being provided with an extension relatively narrower than 35 the body of the plate, said extension being arched to form a continuation of the arch of the said plate and to underlie the ball of the foot, and means arranged in the sole of the shoe for supporting the said extension 40 and regulating the height thereof.
11. The combination of a shoe, and an arch support including a plate arched longitudinally arranged on the inside of the shoe, the forward end of said plate being provided with an extension relatively narrower than 45 the body of the plate, a plate disposed beneath the said extension, a tubular member threaded interiorly to which the last-mentioned plate is secured, a tubular member secured in an 50 opening in the shoe sole in which the said

first-mentioned tubular member is slidable, and a screw extending inwardly through the sole of the shoe and engaging the interior threaded opening in the first-mentioned tubular member, providing means for adjusting the height of the first-mentioned tubular member and the said extension. 70

12. The combination of a shoe, and an arch support including a plate arranged on the inside of the shoe, the forward end of said 75 plate being provided with an extension relatively narrower than the body of the plate, a plate secured to the inner sole of the shoe, said plate being provided with a tubular extension arranged in an opening in the shoe 80 sole, a plate secured to the outer sole of the shoe, a screw provided with a flange adjacent one end thereof, said flange being arranged between the said last-mentioned plate and the end of the said tubular extension, 85 and co-operating means engageable with the said screw for regulating the height of the said forward extension.

13. The combination of a shoe, and an arch support including an arched plate, a tubular member threaded interiorly secured to the 90 said plate, a plate secured to the inner sole of the shoe, said plate being provided with a tubular extension in which the said tubular member is slidably mounted, a plate secured to the outer sole of the shoe, a screw provided with a flange adjacent one end thereof, said flange being arranged between the said 95 last-mentioned plate and one end of the said tubular extension and in position to engage the interior threaded opening of the said tubular member to regulate the height of the arch of the first-mentioned plate, and means tightly securing the plates on the inside sole of the shoe and on the outside sole 100 of the shoe together to prevent entrance of water or moisture through the said tubular extension.

14. The combination of a shoe, and an arch support including a plate arranged on the 105 inside of the shoe, said plate being freely supported at its ends, and means secured to said plate substantially centrally thereof adjacent each side edge securely fastening the said plate to the sole of the shoe. 110

15. The combination of a shoe, and an arch support including an arched plate arranged on the inside of the shoe, means secured to said plate adjacent each side edge thereof for supporting the arch of the plate, means co-operating with the first-mentioned means extending through the sole of the shoe for adjusting the height of said plate at each side edge thereof, and means operable from without the shoe for locking the plate in adjusted 115 position. 120

16. The combination with a shoe or similar article, of an arch support disposed therein, a plurality of collars arranged to bear on the under side of said arch support, means oper- 130

able from the exterior of the shoe for raising or lowering said collars to adjust the position of the arch support, said means comprising a screw, a threaded portion secured to each collar and arranged to receive the screw, and means for preventing the rotation of the said collar when the screw is turned.

17. An arch adjusting member comprising a collar, a cylindrical portion integral with the collar and being threaded internally, a screw having a threaded portion arranged to enter said threaded cylindrical portion and being provided with a flange adjacent to the head of the screw, and a plate having an opening arranged to receive the head and to bear against the flange.

18. An arch adjusting member comprising a collar, a cylindrical portion integral with the collar and being threaded internally, a screw having a threaded portion arranged to enter said threaded cylindrical portion and being provided with a flange adjacent to the head of the screw, a plate having an opening arranged to receive the head and to bear against the flange, said plate being provided with openings, and means for securing the plate to the bottom of a shoe or similar article.

19. The combination with a shoe or similar article, an arch support therefor, a cylindrical member threaded internally secured to said arch support, a screw having a portion arranged to enter said cylindrical member, said screw having its head disposed in the sole of the shoe flush with the bottom thereof and operable from the exterior of the shoe to raise or lower the arch support, and means for preventing the longitudinal movement of the screw when it is turned.

20. The combination with a shoe or similar article, an arch support therefor, a cylindrical member threaded internally secured to said arch support, a screw having a portion arranged to enter said cylindrical member, said screw having its head disposed in the sole of the shoe flush with the bottom thereof, means for preventing the longitudinal movement of the screw when it is turned, and means for preventing the rotation of the cylindrical member when the screw is turned.

21. An adjusting device for arch supports comprising a collar having a threaded cylindrical extension on one side thereof, a flange having an extension on one side thereof arranged to receive the extension of the said collar, a screw having a threaded portion arranged to engage the threaded portion of said collar, said screw being provided with a flange, and a head on the opposite side of the flange from the threaded portion, and a plate having an opening arranged to receive the head of the screw.

22. An adjusting device for arch supports comprising a collar having a threaded cylindrical extension on one side thereof, a flange

having an extension on one side thereof arranged to receive the extension of the said collar, a screw having a threaded portion arranged to engage the threaded portion of said supporting member, said screw being provided with a flange, a head on the opposite side of the flange from the threaded portion, a plate having an opening arranged to receive the head of the screw, and means for preventing the rotation of the collar with respect to the flange.
